UNITED STATES PATENT OFFICE.

CHARLES W. WEISS, OF BROOKLYN, ASSIGNOR OF ONE-HALF TO CHARLES KRUSE, OF NEW YORK, N. Y.

SEWING-MACHINE.

SPECIFICATION forming part of Letters Patent No. 399,364, dated March 12, 1889.

Application filed December 8, 1887. Serial No. 257,810. (No model.)

To all whom it may concern:

Be it known that I, CHARLES W. WEISS, of Brooklyn, in the county of Kings and State of New York, have invented certain new and useful Improvements in Sewing-Machines; and I do hereby declare that the following is a full and exact description thereof, reference being had to the accompanying drawings, and to the letters of reference marked thereon, making a part of this specification, in which—

Figure 1 is a side elevation, partly in section, of my improved machine with the looper in its extreme forward position; Fig. 2, a similar elevation of the lower portion of the machine, showing the looper in its extreme backward position. Figs. 3 to 6 illustrate the formation of a stitch by the movements of the looper in connection with the needle; Fig. 7, an elevation of the front end of the machine with the parts above the table broken away; Fig. 8, a detached elevation of the looper-shaft and its bearings and of the proximate end of the main shaft, showing the looper midway of its stroke.

Similar letters of reference indicate like parts in all of the figures.

My invention relates to improvements in the construction and operation of the looper or horizontal needle in a double-chain-stitch sewing-machine, and has for its object to simplify the mechanism and obtain greater freedom and rapidity of movement therein.

It consists in the combination, with the reciprocating needle in a sewing-machine, of a longitudinally-perforated looper traversing the path of the needle, and having a compound rotary and longitudinally-reciprocating movement, as hereinafter fully described.

It consists, also, in devices, as hereinafter described and claimed, for imparting the longitudinally-reciprocating and simultaneous rotating movement to the looper in proper correspondence with the vertically-reciprocating movements of the needle.

In the accompanying drawings, A represents the bed-plate; B, the cloth-plate; C, the frame; D, the vibrating needle-arm; E, the needle-bar; F, the presser-foot bar; G, the driving-shaft, and D' the eccentric on said shaft G, by which the needle-arm is oscillated.

The shaft G is longitudinally perforated from end to end. Upon its inner end is mounted a collar, H, from which an arm, I, extends at an angle of about forty-five degrees, more or less. A pedestal, J, is mounted in front of the end of the shaft upon the bed-plate A to support a tubular head, K. The looper-shaft L is fitted to rotate and reciprocate freely within this head, and the head is so inclined as that the rod shall extend at an angle with the cloth-plate B. In the drawings, Figs. 1 and 2, the looper-shaft is shown as inclined in a line which, extending from a point in front or to the left of the needle-hole in said plate, intersects the axis of the shaft G at a point about midway between the end of the shaft and the pedestal J; but this angle may be varied in accordance with the throw or length of reciprocating movement required in the looper, the throw decreasing in proportion as the angle of inclination is reduced and the looper-shaft made to approach a straight line coincident with the axis of the shaft.

An arm, M, is secured to the rear end of the looper-shaft L to project radially therefrom far enough to intersect the arm I of the shaft G, and the two are coupled by a universal joint, which may be formed by a ball upon the end of the arm I fitting in a slot or recess in the end of the arm M or in a detachable block, M', of hard metal secured to the end of said arm, as shown in Fig. 1.

A looper, N, formed of a longitudinally-perforated needle curved at its outer end, as shown in Figs. 1 and 3 to 6 of the drawings, is fitted in the open end of the tubular looper-shaft L to project therefrom as an extension thereof, and is secured by a set-screw, O. The looper N is so adjusted in length as to intersect in the course of its movements the line of travel of the needle, and the two are made to move synchronically by a proper adjustment of the eccentric D', by which the needle-bar is actuated upon the shaft G, by which the looper is actuated.

An eye, P, is secured to the face of the fly-wheel Q, fitted upon the outer end of the shaft G, or otherwise, as an equivalent to an arm projecting radially therefrom, so that the eye shall revolve with the wheel or arm about the

axis of the shaft as the latter rotates. A second eye, R, is mounted upon a post, R', fixed to the bed-plate A at one side of the axis of the shaft and in front of the end thereof, and 5 a spring-actuated tension device, S, of any approved description, is fitted upon a pillar, S', near to the stationary eye R, as shown in Figs. 1, 2, 7, and 8.

In the use of the machine a thread, 3, is led 10 from a spool mounted upon a suitable spool-holder out between the disks of the tension device S, and through the stationary eye R and revolving eye P to the proximate end of the main shaft G, thence through the longitudinal perforation in said shaft to the tubular looper-shaft L, and through said shaft and the looper N out through the end of said looper. The threading of the main shaft, looper-shaft, and looper is readily effected by 15 20 the use of a long slender wire having an eye in its end to engage the thread.

In operation the rotation of the main shaft G will produce in unison with the customary vertically - reciprocating movements of the 25 needle-bar E and needle T, carried thereby, a longitudinally-reciprocating as well as rotary movement of the looper-shaft L and looper N. The looper N is so adjusted in the looper-shaft as that, as it passes forward beyond the line 30 of movement of the needle T at the moment the needle has passed its lowest point and is commencing its upward stroke, so as to form with the thread 1, which it carries, an open loop, 2, the curved end of the looper is 35 turned with its point downward and slightly sidewise in proper position to readily enter said loop 2, as shown in Fig. 3, the needle being on the outer side of the looper. The looper, moving through the loop 2 left by the 40 ascending needle, carries with it the thread 3, extending through the shaft G. As the needle rises, the looper continues its forward movement, and, rotating upon its axis, is so far turned as that by the time it fully reaches 45 the end of its forward stroke (at which time the needle has reached its highest point as shown in Figs. 1 and 4) its curved end is turned upward, and, continuing to revolve as it moves backward, it is turned sidewise as 50 well as slightly upward by the time it again passes under the needle, which, having in the meantime descended, will pass, as shown in Fig. 5, on the inner side of the looper, between it and the thread 3, which it delivers, and in 55 front of the loop 2, still remaining on the looper. As the looper continues its retrograde movement and the needle its descent, the needle passes down between the looper and the thread 3, extending therefrom, and said thread, after 60 being thus engaged by the needle, is drawn through the loop 2, which, as the looper moves back, is slipped off of its point upon the thread 3, thereby forming a stitch, which will be tightened and drawn up to the fabric, as shown in 65 Fig. 6, by the tension produced by the descent of the needle in connection with the backward movement of the looper, as set forth.

As the needle rises, the thread is slackened, so as to produce a loop, through which the looper in its forward movement will again pass, in manner as hereinbefore described and as illustrated in Fig. 3, it having meantime revolved sufficiently to bring its point around into proper position for the purpose. These movements are produced noiselessly and may 70 75 be made with great rapidity and precision. As the shaft G rotates, the eye P, carried thereby, is brought into close proximity to the stationary eye R at the moment the looper has completed its forward stroke. As the looper moves back, the eye P is carried farther and farther from the eye R, thereby tightening the stitch and taking up the slack thread produced by the retrograding movement of the looper, and also drawing more thread from the 80 85 spool sufficient to form a stitch. As the looper is moving forward again, the eye P gradually approaches the eye R, and thereby slackens the thread 3 just drawn from the spool to pass freely forward with the looper, as required in forming a new stitch. The tension of the thread as it is drawn from the spool may be furthermore controlled and kept uniform either by means of a simple tension device, S, consisting of a stationary disk, a, 90 95 against which a movable disk, b, is held by means of a spiral spring, c, as shown in Figs. 1, 2, and 9, (the thread being carried between the disks a b,) or by other of the tension devices known to the art.

By forming a longitudinal perforation through the looper and carrying the lower thread through said perforation I avoid the necessity of using a bobbin or shuttle to carry said lower thread and I prevent the thread 100 delivered by the looper from twisting. I am thereby enabled to form a "Grover & Baker" 105 stitch with the machine by means of a rotating looper instead of a reciprocating hook to carry the lower thread, and to increase also 110 the speed of the machine and the number of stitches formed per minute. Furthermore, the machine may be constructed by my invention in a simpler manner and at a greatly-reduced cost as compared with the machines 115 heretofore constructed for the same work.

I claim as my invention—

1. The combination, with the reciprocating needle in a sewing-machine, of a looper which has a rotary movement about its longitudinal axis and a simultaneous reciprocating movement in the direction of said axis, and which is formed with a longitudinal perforation extending through it, substantially in the manner and for the purpose herein set 120 forth.

2. The combination, with the reciprocating needle in a sewing-machine, the main rotating shaft actuating the same, and a looper-shaft and looper mounted to rotate and reciprocate upon its longitudinal axis in front of the end of said main shaft and to traverse the path of the needle, of an arm projecting radially from the end of the main shaft outwardly 125 130

at an angle therewith, and a crank-arm upon the proximate end of the looper-shaft coupled to said radial arm by a universal joint, substantially in the manner and for the purpose 5 herein set forth.

3. The combination, in a sewing-machine, of the longitudinally-perforated rotating shaft G, the longitudinally-perforated looper-shaft L, rotating and reciprocating upon its longitudi- 10 nally-perforated looper N, carried by the shaft L, and the reciprocating needle T, traversing the line of movement of the looper, substantially in the manner and for the purpose herein set forth.

4. The combination, in a sewing-machine, of the longitudinally-perforated rotating shaft G, the longitudinally-perforated looper-shaft L, rotating and reciprocating upon its longi- 20

tudinal axis at an angle with said shaft G, the crank-arm M upon the inner end of said looper-shaft, the outwardly-inclined radial arm I, fitted upon the proximate end of the shaft G and coupled to said crank-arm M by a universal joint, the curved longitudinally-perforated looper N, fitted to the opposite end of the looper-shaft L, a reciprocating needle, 30 T, traversing the line of movement of the looper to intersect the same, and mechanism, substantially as described, for actuating the needle by means of the rotation of the shaft G, all substantially in the manner and for the 35 purpose herein set forth.

In testimony whereof I have signed my name to this specification in the presence of two subscribing witnesses.
